Inventor =

UNITED STATES PATENT OFFICE.

WILLIAM H. JAMOUNEAU, OF NEWARK, NEW JERSEY.

DESIGN FOR A SPOON, &c.

SPECIFICATION forming part of Design No. 20,956, dated July 21, 1891.

Application filed June 6, 1891. Serial No. 395,389. Term of patent 7 years.

To all whom it may concern:

Be it known that I, WILLIAM H. JAMOUNEAU, a citizen of the United States, residing at Newark, in the county of Essex and State 5 of New Jersey, have invented and produced a new and original Design for Spoons, Forks, and Similar Flat Ware; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 The single view of the drawing is a plan showing the front of a spoon, the one illustration being deemed sufficient to indicate the novel features of the design.

The novel feature of the invention consists 20 in the scroll-shaped handle with open-work face, substantially as shown, and will now be described.

In said drawing, *a* indicates the handle, and *b* the bowl of the spoon. The said handle is in the shape of a series of scrolls *c c c'*, 25 which increase in size toward the extremity of the handle. The scroll *c'* at the extremity is of open-work. *d d d* are the perforations therein. The middle scroll faces in a direction opposite from those next adjacent. 30

What I claim as new is—

The design for the handle of a fork, spoon, or other article of flat ware, which consists in the handle having the shape of a series of enlarging and oppositely-facing scrolls, the 35 largest one of which is perforated, substantially as shown and described.

In testimony that I claim the foregoing I have hereunto set my hand this 26th day of May, 1891.

WILLIAM H. JAMOUNEAU.
